UNITED STATES PATENT OFFICE.

CHARLES L. HOLDEN, OF INDIANAPOLIS, INDIANA.

RANGE-BOILER STAND.

1,182,564.

Specification of Letters Patent.

Patented May 9, 1916.

Application filed April 15, 1915. Serial No. 21,589.

To all whom it may concern:

Be it known that I, CHARLES L. HOLDEN, a citizen of the United States, residing at Indianapolis, in the county of Marion and 5 State of Indiana, have invented a new and useful Range-Boiler Stand, of which the following is a specification, reference being had to the accompanying drawings, and to the letters and figures of reference marked 10 thereon.

The invention relates to adjustable stands for supporting cylindrical tanks or range boilers on end and to permit a drainpipe to extend down through the stand, the adjustability of the stand being such as to accommodate range boilers that may be varied 15 slightly in diameter and also those of different capacities and diameters.

An object of the invention is to provide 20 an improved range boiler stand which shall be so constructed of very few and simple parts as to be cheaply produced and be strong and reliable and also readily adjusted.

25 Another object is to provide an improved adjustable stand that shall be adaptable to be shipped in knock-down condition and permit of being easily set up for use without requiring other than the ordinary tools 30 usually carried by workmen.

A further object is to provide a stand which shall have a wide range of adjustment and comprise connecting parts that may 35 suitably be composed of wrought metal and of light weight and not be liable to become fractured, and be durable and economical in use.

A still further and more specific object is 40 to provide a range boiler stand having stand- 45 ard or leg members of such construction as to be strong and permit them to be readily shortened or lengthened in case of necessity to accommodate the stand to uneven cement or other floors, or to various other condi-

With the above-mentioned and other ob- 50 jects in view, the invention consists in a range boiler stand comprising a plurality of standards that are all cast from a single pattern, and a plurality of devices for connecting the standards together, all of identi- 55 cal pattern, each part being of novel construction; and the invention consists fur- rangers of parts, as hereinafter particu-

larly described and further set forth in the accompanying claims.

Referring to the drawings,—Figure 1 is a side elevation of the improved range boiler stand and a boiler thereon partially broken 60 away; Fig. 2 is a top plan of the stand; Fig. 3 is a perspective view of one of the connectors whereby the standards are adjustably connected together; Fig. 4 is a horizontal section on the line A A on Fig. 1; Fig. 5 is 65 a perspective view of one of the standards; Fig. 6 is a fragmentary section corresponding to a portion of Fig. 4, but on an enlarged scale and with parts differently adjusted; and, Fig. 7 is an inverted plan view 70 of the standard.

Similar reference characters indicate cor- 75 responding elements or features of construction throughout the different figures of the drawings as hereinafter referred to in detail.

The improved stand is designed to sup- 80 port a tank or range boiler 1 in upright po- sition, a drain-pipe 2 being in some cases connected to the bottom of the tank or boiler so as to extend downward to or through a 85 floor. The stand comprises a plurality of standards 3, 3', 3'', that are normally ar- ranged uprightly and are provided respec- 90 tively with lateral arms 4, 4', 4'', the tops of the standards having seats 5, 5', 5'', re- 95 spectively, on which to support the tank or boiler and having also guide projections 6, 6', 6'', respectively, that are brought to the exterior of the tank or boiler by adjustment of the standards each with respect to the 100 other. The standards have lower leg por- 105 tions 7, 7', 7'', respectively, each portion having a plurality of vertical ribs 8, 9, 10 and 11 thereon which strengthen the other- wise relatively thin leg portions. In case it is found desirable to shorten one or more of the leg portions the ribs may be easily sawed into transversely by means of a hack-saw, after which the weakened leg portion may be easily fractured, the end portion of the 100 metal being removed thus shortens the standard and obviates the necessity of leveling a concrete or a brick floor. A piece of pipe 7^a is driven over the ribs to lengthen the leg portions.

The arm of each standard has two bolt 105 holes 12 and 13 therein spaced apart and horizontally arranged, a suitable number of bolts 14, 14', 14'', being provided for inser- 110 tion into the holes, one for each arm, so that 115

each bolt may be inserted into either one of the two holes. The arms are provided respectively with a pair of guide wings 15 and 16, 15' and 16', 15" and 16", the two wings 5 of the pair being on opposite sides respectively of the arm and between the two bolt holes.

The connector for the standards comprises a plurality of members having curved 10 main portions 17, 17', 17", respectively, on the ends of which are straight extensions 18, 19, 18' and 19', 18" and 19", the two extensions of each member being placed on the side of two of the standard arms, so 15 that each arm is between the extensions of two of the members. One extension of each member has a longitudinal slot 20 therein, the other extension having a similar slot 20' therein. The slots of two extensions are 20 ranged as a pair on opposite sides of an arm receive the guide wings of the arm and also the securing bolt and permit them to slide when the bolt is loosened for adjusting the standard relatively to the connector.

25 In practical use, in case the stand must be adjusted for the smaller size of tank or boiler, the securing bolts are placed in the holes 12 and may be adjusted in the slots to compensate for any discrepancy, as between the listed nominal diameter and the 30 actual diameter of the boiler, each slot being sufficiently long to permit sliding movement of the wings and the bolt. In case a larger tank or boiler must be supported, the bolts are placed in the holes 13 after 35 the arms are drawn outward, the arrangement then being as shown in Fig. 6, when further adjustment may be made if required. When the required adjustments 40 have been made the nuts on the securing bolts are tightened and securely clamp each standard arm between two extensions of the connector. In case it is found that the stand is not level on a permanent floor 45 which could not be conveniently leveled, the workmen may quickly shorten one or more of the leg portions of the standards by filing or cutting off the end of the extension 7^a, as may be required to level the 50 stand. Likewise the leg portions may be cut into and broken off if found desirable or necessary to reduce the height of the stand; also various lengths of pipes or tubes 55 may be placed on the leg portions if required.

Having thus described the invention, what is claimed as new is—

1. A standard for a range boiler stand, said standard comprising a main portion 60 with a seat on its top and also a lateral arm to be connected with the arms of like standards, a straight leg portion that is relatively less in diameter than the main portion extending from the main portion 65 below the arm, and ribs radially fixed on

the leg portion, the ribs being co-extensive in length with the leg portion and fixed at their upper ends to the main portion of the standard in proximity to said arm.

2. A range boiler stand comprising standards having each an arm provided with two separate bolt holes and two horizontal guide wings between the holes and on the two opposite sides respectively of the arm, a bolt for each arm in one of the two holes, 75 and a connector comprising coöperating members having slots receiving the guide wings and the bolts, the bolts securing the arms to the connector.

3. A range boiler stand comprising a plurality of standards, each having a lateral arm thereon provided with two separate bolt holes and two horizontally projecting guides between the holes and on the two opposite sides respectively of the arm, and 80 a connector comprising a plurality of members having slots receiving the guides, there being two slots in each member, one receiving one of the guides of one of the arms, the other slot receiving one of the guides 85 of another one of the arms, one slotted portion of one member being on one side of an arm, one slotted portion of another member being on the opposite side of the arm, and a plurality of securing bolts connecting 90 the arms to the connector, one bolt for each arm in one of the holes thereof and extending through the slots of the adjacent connector members.

4. In a range boiler stand, a plurality 100 of normally upright standards to be connected together, each standard comprising a main portion with a seat on its top and also a lateral arm to be connected with the arms of the remaining standards, a straight 105 leg portion extending from the main portion below the arm, ribs radially fixed on the leg portion, and a hollow cylindrical leg part embracing all the ribs and extending from the main portion of the standard 110 and downward beyond the lower end of said leg portion.

5. In a range boiler stand, the combination of a plurality of normally upright standards, each standard having an arm 115 thereon provided with two separate bolt holes and two horizontally-projecting guides between the holes and on the two opposite sides respectively of the arm, the standard having also a leg portion that extends therefrom at approximately right angles to the arm and has relatively narrow ribs radially arranged thereon, the ribs being co-extensive with the leg portion and fixed at their upper ends to the standard 120 in proximity to said arm, a plurality of connector members each having two slots receiving the guides of two of the arms, one slotted portion of one of said members being on one side of the arm, one slotted por- 125

tion of another member being on the opposite side of the arm, and a plurality of securing bolts connecting the arms to the members, there being one bolt for each arm
5 in one of the holes thereof and extending through the slots of the adjacent connector members.

In testimony whereof I affix my signature in presence of two witnesses.

CHARLES L. HOLDEN.
